CLAIM

The ornamental design for a waveguide converter as shown and described.

DESCRIPTION

FIG. 1 is a front view of a waveguide converter showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front, left side, bottom perspective view thereof, and,

FIG. 8 is a front, left side, bottom perspective view thereof, shown in a state of use with the lid removed.

The dashed lines in the drawings depict portions of the waveguide converter that form no part of the claimed design. The dashed-dotted lines in the drawings depict the boundaries of the claimed design and form no part thereof.
